2 Sheets-Sheet 2

UNITED STATES PATENT OFFICE.

JOHN WEARHAM, OF WESTMINSTER, LONDON, ENGLAND, ASSIGNOR TO VICKERS LIMITED, OF WESTMINSTER, LONDON, ENGLAND, A BRITISH COMPANY.

PNEUMATIC PIANO PLAYER.

Application filed July 6, 1922. Serial No. 573,124.

To all whom it may concern:

Be it known that I, JOHN WEARHAM, a subject of the King of Great Britain, residing at Vickers House, Broadway, Westminster, in the county of London, England, have invented new and useful Improvements in or Relating to Pneumatic Piano Players, of which the following is a specification.

This invention relates to pneumatic piano players in which the strikers are controlled by a moving perforated or slotted music roll or sheet. The invention is especially intended for use with the piano player forming the subject of British Patent No. 186680 but it is to be understood that the said invention is not restricted to such use as it is capable of being employed in connection with other forms of piano players.

According to the present invention the music roll or sheet and the pumping device which supplies air under pressure to the wind box or chest (or which exhausts air therefrom) for operating the pneumatics are manually actuated by means of a crank having a plate or disc upon which the palm of the operator's hand rests. This plate or disc may carry a member between which and the plate or disc the operator's hand is slipped, the necessary grip being preferably obtained by pressure of the fingers upon the plate or disc so as to bring the back of the hand into firm contact with the said member.

Means may be provided for causing the stroke that is given to the feeding bellows to vary automatically in accordance with the position occupied by the movable element of a pressure regulating reservoir with which the said bellows communicates. For this purpose the shaft of the crank may carry a cam operating the movable element of the feeding bellows which is carried by the movable element of a large bellows or pressure regulating reservoir with which the former bellows communicates. The arrangement is such that as the store of air in the large bellows accumulates, or as the degree of suction therein increases, as the case may be, depending on the type of piano player to which the invention is applied, the roller on the feeding bellows will occupy different positions giving decreasing amplitudes of

movement to the bellows; in this manner over-pumping is avoided and no sudden change of load will be thrown upon the hands.

In order to vary the force with which the pneumatics operate, the aforesaid plate or disc may be so mounted that it can be turned about an axis at right angles to its surface during the rotation of the crank and means are provided whereby the turning movements are transmitted to the device controlling the force with which the pneumatics operate.

In an alternative arrangement the movable plate of the feeding bellows may normally occupy an inclined position so that its upper edge (which is preferably pivoted) is situated further away from the operator than the lower edge and this plate may have a leather or other suitable strap or bridge member for receiving the operator's hand. The said plate may also carry one or more levers or other devices for varying the force or tempo with which the pneumatics operate, this device being preferably actuated by lateral movements of the operator's hands upon the plates or by the thumbs of the operator.

In order that the said invention may be clearly understood and readily carried into effect the same will now be more fully described with reference to the accompanying drawings, in which:—

Figure 1 is a sectional side elevation showing a constructional form of the invention,

Figure 2 is a plan of Figure 1 with the driving plate or disc shown inverted,

Figure 3 is a section taken approximately on the line 3, 3 of Figure 1 and viewed from the right hand side,

Figure 4 is a section taken approximately on the line 4, 4 of Figure 1 and viewed from the right hand side,

Figure 5 is a perspective view showing diagrammatically a modified constructional form of the invention and Figures 6 and 7 are views of details hereinafter referred to.

Referring to Figures 1 to 4, A is the driving cylinder or take up spool for the music sheet A¹, A² is the cylinder from which the music sheet is drawn on to the former cylinder and A³ is the tracker bar over which the

music sheet passes. B is the wind box, B¹ is the aforesaid large bellows or pressure regulating reservoir communicating with this wind box and B² is the small feeding bellows mounted on the bellows B¹. C is the aforesaid operating crank and C¹ is the aforesaid plate or disc having a bridge member C² which is suitably padded and between which and the disc C¹ the operator's hand is placed as aforesaid. Rigidly connected to the disc C¹ is a cam C³ and the combined disc and cam are pivoted at C⁴ to a base member C⁵ having lugs C^{5x}, C^{5x} through which the horizontal portion C^{1x} of the crank loosely passes. This cam operates upon a roller carried by a sleeve C⁶ slidably mounted on the portion C^{1x} of the crank which sleeve is joined by a member C⁷ to a sleeve C⁸ slidably mounted on the crank shaft. The member C⁷ is of half-tube section so as to partly enclose the side of the crank. The sleeve C⁸ is spring controlled and has a collar operating upon a pivoted arm C⁹ connected by a cord C^{9x} to any suitable device controlling the force with which the pneumatics operate. Such a device is shown in Fig. 6 and comprises a small bellows C¹⁰ having a pipe C¹¹ leading to the main air reservoir and a pipe C¹² leading to the wind chest of the striking motors or pneumatics. The inovable plate of this bellows carries a shutter C¹⁰ which moves over a lateral aperture C¹² communicating with the interior of the pipe C¹². The cord C^{9x} is connected to the said movable plate. The disc C¹ has a pointer C¹ moving over an expression scale C⁵ attached to the base member C⁵. C^x is the aforesaid cam which is operated by the crank and engages with a roller b³ on a spring controlled arm B³ pivoted at b^{3x} to a fixed part. This arm engages with a roller b² on the movable element of the feeding bellows B². As the degree of suction in the large bellows B¹ (with which the feeding bellows B² communicates by a pipe b¹) increases and the movable element of the bellows B¹ moves downwards in consequence, the roller b² will be brought gradually and smoothly into different positions along the arm B³ so that the amplitude of movement given by the cam C^x to the movable element of the bellows B¹ will be varied to suit the different requirements. When the roller b² comes opposite the pivot b^{3x} no stroke will be imparted to the movable element of the bellows B¹. The said cam is preferably shaped as shown in Figure 4 so that the major portion of the work is performed during the forward movement of the crank, namely at the time when the operator tends to exert the greatest turning moment upon the crank shaft, and the return or inoperative movement of the bellows B² takes place during the movement

of the crank towards the operator, when the tendency is to exert a lesser turning moment upon the crank shaft. In this manner the effect of a uniform and balanced operation of the crank can be obtained which is important for driving the music sheet. When this portion of the invention is employed in conjunction with a piano player in which the pneumatics are operated by air compressed by the bellows B² the arrangement of the cam C^x and its associated parts would be suitably modified so as to obtain the desired action.

Two of the aforesaid cranks and pumping devices are preferably employed arranged one at each side of the central portion of the piano player containing or carrying the music roll or sheet. The crank at the left hand side has no operative connection with the cylinders A, A²; it may however have a device similar to that hereinbefore described for varying the force with which the pneumatics operate and in this case the pneumatics appertaining to the higher notes would be controlled by the device on the right hand crank and those appertaining to the lower notes would be controlled by the device on the left hand crank. As the fingers of the operator's hands are extended in close contact with the actuating plates or discs and are moved up and down during the operation of the latter, some resemblance exists between the operator's movements and those employed in ordinary pianoforte playing.

The driving mechanism for the music sheet comprises in the example shown a friction wheel a on the aforesaid crank shaft which wheel presses against a band or belt a¹ passing over an idle wheel a^{1x} on an arm of a spring controlled member a² pivoted at a^{2x}. The said band or belt passes over a pulley a³ connected to the spindle a⁰ of the driving cylinder A. The crank shaft also carries a sprocket wheel a⁴ connected by a chain a^{4x} to a smaller sprocket wheel a⁵ which is connected by a friction wheel a⁶ to another friction wheel a^{6x} carried by another arm of the member a². The wheels a⁵ and a⁶ are mounted coaxially with the pivot a^{2x} of the member a². This member normally occupies the position shown by Figure 3 in which the friction wheel a^{6x} is in contact with a small friction wheel a^{6x} on a spindle carrying a centrifugal device a⁷ which operates a speed indicating pointer a^{7x}. When the said member is moved in an anti-clockwise direction (Figure 3) by a handle a⁸, the driving connection between the crank C and the cylinder A is interrupted owing to the bodily movement of the wheel a^{1x} away from the wheel a, and the friction wheel a^{6x} is brought into contact with a small friction wheel a⁸ on the spindle of the cylinder A², thereby establishing a

driving connection between the crank shaft and the cylinder A² for re-winding the music sheet from the driving cylinder A; at this time the operative connection between 5 the friction wheel a^{6x} and the speed indicating pointer a^{7x} is interrupted owing to the bodily movement of this wheel away from the wheel a⁶ appertaining to the centrifugal device a⁷. Spring controlled brakes a⁹, a^{9x} 10 are provided on the member a² for braking the cylinder A² when the member a² is in the position shown by Figure 3 and for freeing this cylinder and braking the other cylinder A when the said member is moved 15 as aforesaid into the position for re-winding the music sheet on the cylinder A².

In the modified construction shown by Figure 5 D represents the movable plate of the bellows arranged at an inclination as 20 shown and pivoted at its rear upper edge to the fixed plate D¹ of the bellows. The latter plate constitutes one of the walls of the wind box or chest D² which is of triangular form in cross section. D³ is a strap or bridge 25 piece between which and the plate D the operator places his hand in order to operate the bellows. D⁴ is a small handle pivoted to the plate D and connected to a crank D⁵ to which is attached a cord D⁶ leading to the 30 device for varying the loudness. This device may be similar to that shown in Figure 6, the cord D⁶ being connected to the movable plate of the bellows. A second small handle similar to the handle D⁴ may be provided 35 for varying the tempo. For this purpose this second handle is connected to a second crank similar to the crank D⁵ and to this second crank is attached a cord D⁷ (Fig. 7) connected to a slide valve D⁸ which 40 controls ports d⁷ and d⁸ communicating with pipes d^{7x} and d^{8x} which lead respectively to the main air reservoir and to the pneumatic motor for driving the music roll.

It is to be understood that the term "piano 45 player" herein employed is intended to include players for keyboard instruments similar to pianos.

What I claim and desire to secure by Letters Patent of the United States is:—

50 1. In a pneumatic piano player, the combination with a pumping device, of a crank for actuating said device and a plate on said crank upon which plate the operator's hand rests in actuating the crank.

55 2. In a pneumatic piano player, the combination with a pumping device, of a crank for actuating said device, a plate on said crank upon which plate the operator's hand rests in actuating the crank and a bridge 60 member on said plate between which member and plate the operator's hand is passed.

3. In a pneumatic piano player of the kind in which the mechanism is governed by a perforated music sheet, the combination

with the elements claimed in claim 1, of a 65 driving cylinder for the music sheet and means for operating said cylinder from the crank.

4. In a pneumatic piano player of the kind in which the mechanism is governed 70 by a perforated music sheet, the combination with the elements claimed in claim 2, of a driving cylinder for the music sheet and means for operating said cylinder from the crank. 75

5. In a pneumatic piano player, the combination with the elements claimed in claim 1, of an air pressure regulating reservoir, a feeding device in communication with said reservoir and means for causing a stroke to be imparted to said device, means for automatically varying said stroke in accordance with the position occupied by an element of said reservoir moving in accordance with the pressure conditions in the reservoir. 80

6. In a pneumatic piano player, the combination with the elements claimed in claim 1, of an air pressure regulating reservoir, an element thereof moving in accordance with the pressure conditions in the said reservoir, 90 a feeding bellows mounted on said movable element and placed in communication with said reservoir, and a device mounted on a stationary part for operating said bellows. 95

7. In a pneumatic piano player, the combination of an air pressure regulating reservoir, an element thereof moving in accordance with the pressure conditions in the said reservoir, a feeding bellows mounted on said movable element and placed in communication with said reservoir, a cam for operating said bellows and a pivoted member interposed between said cam and the movable element of said bellows. 100

8. In a pneumatic piano player having pneumatics for operating the keys, the combination with the elements claimed in claim 1, of means for pivoting the plate so that it can be turned about an axis at right angles to its surface during the rotation of the crank, a cam moving with said plate and means whereby said cam operates to vary the force with which the pneumatics operate. 105

9. In a pneumatic piano player, the combination with a feeding bellows having a movable plate which normally occupies an inclined position with its upper edge situated further away from the operator than the lower edge, of a bridge piece carried by said plate between which bridge piece and said plate the operator's hand is passed. 115

10. In a pneumatic piano player having pneumatics for operating the keys, the combination with the elements claimed in claim 9 of a controlling element carried by the 120 movable plate for varying the expression produced by the operation of the pneumatics. 125

JOHN WEARHAM.
